UNITED STATES PATENT OFFICE.

FRANCIS A. SKELTON, OF NEWTON, MASSACHUSETTS.

MESSAGE-RECORDING APPARATUS.

938,441.

Specification of Letters Patent. Patented Oct. 26, 1909.

Application filed October 28, 1908. Serial No. 459,822.

To all whom it may concern:

Be it known that I, FRANCIS A. SKELTON, a citizen of the United States, and resident of Newton, county of Middlesex, State of 5 Massachusetts, have invented an Improvement in Message-Recording Apparatus, of which the following description, in connection with the accompanying drawing, is a specification, like characters on the drawing 10 representing like parts.

This invention has for its object the production of novel, simple and efficient apparatus for recording electrically transmitted messages, my invention being particularly 15 adapted for use in connection with municipal telegraph or signaling systems wherein any desired one of a set of definite signals or messages can be transmitted from sub-stations to headquarters, as in the case 20 of police and fire-alarm signal-apparatus. In such systems the sub-stations are usually boxes located at suitable intervals in the street, and the messages or signals can be turned in from any one of the boxes by an 25 authorized person, citizen or patrolman, or both, as the case may be.

There are numerous systems for the purposes set forth, and a police signal system is shown and described in United States Patent No. 380779 granted to Wilson April 10, 30 1888, the incoming signals being received at a central station and being recorded by a register which effects feed movement of a record-receiving strip upon which the signal 35 or message is printed by a combination of dots and dashes. The recording operation requires the use of a printing member, such for instance as a marking roll, intermittently brought into contact with the moving 40 record-receiving strip for a long or short interval, as called for by the incoming message, means to supply the printing member with ink being also provided. The use of ink is objectionable for various reasons, but 45 when the printing mechanism is operating properly a clear and legible record is made, which can be instantly and easily read.

In my present invention I eliminate altogether the use of ink or similar material, 50 and make the desired record by slotting the record-receiving member, preferably the usual strip or ribbon of paper, the length of each slot being determined by the electrically-controlled means by which the message 55 is transmitted and by which the operation of the slotting device is governed. That is,

short slots correspond to dots, and dashes are represented by longer slots.

It is usual to so arrange the registering mechanism that the messages coming in 60 from a plurality of sub-stations will be recorded on the one record-receiving strip, the feed movement of the strip being begun automatically when a message is turned in, and it is of great importance that practically 65 no resistance be offered to the uniform feed of the strip. That is, if a message is coming in a second or a third message may come in, in rapid succession or a plurality of messages may come in at once, and 70 manifestly if any of the record-making devices acts to impair the uniform feed of the strip not only will that particular message be recorded incorrectly, but all others which may come in at the same time 75 will be recorded improperly, resulting in great confusion and preventing any proper reading of a message. Hence in using a device to record the message by slots it will be at once obvious that no retardation or stoppage of the feed movement of the strip can 80 be permitted. If a short slot is made, corresponding to a dot, the slotting member enters and is instantaneously withdrawn from the strip, so quickly that the retardation of the strip is very slight, and might possibly be of no great importance, but when the slotting member must remain in engagement with the moving strip for an appreciable period of time a very different problem 85 is presented. The retarding action upon the strip due to such longer engagement with the slotting member must be eliminated and irregular tearing of the strip must also 90 be avoided. Another factor of relatively less importance is the resistance to withdrawal of the slotting member after it has 95 penetrated the moving strip, for the path of movement of the slotting member intersects the path along which the paper strip is moving, and engagement of the strip and said member tends to stop feed of the strip and to hinder withdrawal or disengagement 100 of the slotting member.

Having these various tendencies and requirements in mind I have devised a slot-forming recording apparatus which embodies in its construction and operation the required freedom of action and which eliminates the objectionable features and tendencies hereinbefore pointed out. To that end 105 the slotting member is so mounted upon its 110

movable carrier, and is so constructed, that after penetration of the moving strip the said member moves bodily in unison therewith while in engagement with the strip, 5 whether the slot be long or short, the duration of engagement corresponding, and if a slot longer than one corresponding to a dot is to be made the said slot is formed cleanly with a shearing cut by the action upon the 10 strip of successive portions of a part of the slotting member as it is moved across the plane of movement of the strip while said member is also moved in unison with the strip. The maximum slot is determined by 15 the length of the shearing or cutting edge of the slotting member, and said member will be automatically disengaged from the strip even should the controlling magnet be energized, while for short dash-like slots the dis- 20 engagement takes place simultaneously with the deenergizing of the controlling magnet. By eliminating any tendency of the slotting member to retard or stop feed movement of the strip I am enabled not only to 25 record each message cleanly and in an accurate and well-defined manner, but to use my apparatus as a multiple-signal recorder, for any convenient number of messages may be simultaneously recorded, depending upon 30 the width of the record strip.

The various novel features of my invention will be fully described in the subjoined specification and particularly pointed out in the following claims. 35 Figure 1 is a side elevation of a recording apparatus embodying one form of my invention, the slotting member being shown in operative engagement with the record-receiving member at the instant it has penetrated said strip; Fig. 2 is an enlarged detail showing in full lines the slotter after it has penetrated the strip and is being moved in unison with the latter to continue the slot, the dotted lines showing the slotter as 40 just leaving the strip after the formation of a slot of maximum length; Fig. 3 is a perspective view of a portion of the record-receiving member with slots therein, to illustrate the action of the slotter; Fig. 4 is an 45 end elevation of the parts illustrated in Fig. 2. Fig. 5 is a top plan view of a multiple-signal set, showing four slot-forming devices arranged side by side, the cores of the 50 magnets and the supports for the armatures being shown in section. 55

I will first describe one practical embodiment of my novel recording apparatus herein illustrated and referring to Fig. 1 a suitable electro-magnet 1 is arranged to have its 60 poles 2 coöperate with an armature 3 pivotally mounted at 4 on a bracket 5 depending from a convenient overhead stand 6 supporting the magnet in inverted position. The retractive movement of the armature is 65 limited by a stop-screw 7 adjustably sup-

ported in a port 8 rising from the base B, the end of the armature being beveled at 9 to coöperate with the stop-screw in its adjusted position. Said armature is provided with a transverse, rounded rib 10 at the left 70 of the fulcrum 4, to support the inner end of a carrier 11, connected with the armature by screws 12 on opposite sides of said rib, so that by tightening one and loosening the other screw the outer, left hand of the carrier may be raised or lowered relatively to the armature, the carrier thus being in practice an adjustable extension of said armature, normally rigid therewith. The outer 75 end of the carrier 11 is bifurcated to present parallel ears 13 between which the slotting member is pivoted at 14 above the path of movement of the record-receiving member, which is a long paper ribbon or strip R, such as commonly used in recording apparatus employed in connection with electric signaling systems. A retracting spring 16 is attached at one end to the armature 3 on the side of its fulcrum 4 opposite to the magnet 1, the other end of said spring being 80 carried around a stud 16' and attached to an adjusting screw 17 on the bracket 5, rotation of the screw in one or the other direction increasing or decreasing the tension of the spring, as may be necessary. From an 85 inspection of Fig. 1 it will be manifest that the spring not only moves the carrier away from the strip R to normal, inoperative position, but it also serves as the retracting instrumentality for the armature 3 when the 90 magnet 1 is deenergized, at such time holding the armature against the adjustable stop or detent 7. Said detent 7 also acts through the armature to limit the retractive movement of the carrier as will be apparent. 95

It will be observed that whenever the magnet 1 is energized the attraction of the armature 3 will depress the free end of the carrier 11, and in the present embodiment this movement is arranged to move the slotter into engagement with the record-receiving member or strip R to penetrate and slot the same, each attraction of the armature effecting a slot the length of which is determined by the duration of the period during which the magnet continues to be energized. That is, if a signal is transmitted over the signaling circuit consisting of, say, three short breaks and one long one, (said circuit being normally closed) correspond- 100 ing to three dots and a dash, the armature 3 will be attracted and held for three successive short periods and then for a longer period, and the record on the strip will appear as three short slots and one longer one, 105 as shown in Fig. 3. 110

The slotter is of peculiar construction, and is herein shown as having a substantially triangular shape, made of stiff plate metal, such as hard brass or steel, as desired, the 115 120 125 130

body 18 being pivoted at its upper corner at 14 between the ears 13 of the carrier 11, the upper edge 19 of the body normally being held against the end of an adjustable stop-screw 15 on the carrier by means of a light spring 20 attached at one end to the carrier and at its other end to a lateral pin 21 on the body of the slotter. The spring is only strong enough to prevent accidental movement of the slotter relatively to the carrier, the extreme movement of said slotter against the action of the spring being limited by a stop finger 22 on the outer end of the carrier 11, Figs. 1 and 2. The spring 20 always remains below the pivot 14, so that even should the slotter be swung forward and outward far enough to engage the stop finger 22 said spring will be in condition to return the slotter to normal position relatively to the carrier, as shown in Fig. 1.

The lower corner of the slotter is prolonged to form a pointed or substantially V-shaped penetrating tooth 23, and the rear or lower edge 24 of the body is made as a circular arc extending from the tooth to the point 25, struck from the pivot 14 as a center, and of such radius that when the armature is attracted, as in Fig. 1, the curved edge 24 will continuously intersect and pass across the plane of the record-receiving strip R if the slotter is swung on its pivot 14 until the point 25 contacts with the surface of the strip. Beneath the penetrating tooth I provide a support for the strip, made as a rotatable roll 26, having an annular groove 27 therein slightly wider than the transverse thickness of the tooth 23, and of such a depth that the tooth will clear the bottom of the groove when in the position shown in Fig. 1.

The record-receiving strip R is drawn from a suitable reel R^x, Fig. 1, around a guide-roll 28 and thence forward in a preferably horizontal path over the supporting roll 26 and between two feed rolls 29, 30, the former being positively rotated when a message is to be recorded, imparting feed movement to the strip R in the direction of arrow 31.

The mechanism for rotating the feed rolls may be of any suitable construction, connected with a pinion 32 on the roll 29, the mechanism forming no part of my invention, one form of such mechanism being shown in United States Patent No. 426554, dated April 29, 1890, the upper roll 30 being yieldingly held against the strip by a spring 33.

In recording apparatus of this class it is common to effect feed of the record-receiving strip at a uniform speed when a message is sent in, the feed being automatically started and stopped, as is well known to those familiar with such apparatus. Supposing that the recording apparatus is at rest, Fig. 1, and a message is sent in from

a sub-station, it being understood that the magnet 1 is included in a relay circuit, and that the signaling circuit is normally closed. When the message is sent in the feed-rolls 29, 30 are automatically set in motion and feed movement of the record-receiving strip R begins, and when the magnet 1 is energized by closure of the relay circuit the armature 3 is attracted, thereby depressing the outer end of the carrier 11 and moving the slotting member 18 toward the strip, the pointed tip of the tooth 23 penetrating the strip and passing into the groove 27 of the supporting roll 26, as in Fig. 1.

Referring to Fig. 1 it will be seen that the tip or point of the tooth 23 is at such time a slight distance behind or to the right of the center of the grooved roll 26, the slotter being set for this purpose by means of the adjustable stop-screw 15, in order to leave an unbroken portion of the strip R between successive short slots corresponding to short dashes, but longer than the shortest slots which correspond to dots. Remembering that the strip R is moving forward at a uniform speed and that its feed movement must not be retarded or stopped, when the tooth 23 penetrates the strip a short slot or perforation is made, and if the impulse is short the magnet 1 is instantly deenergized and the spring 20 retracts the armature and lifts the carrier and the slotter to normal position, the tooth 23 being withdrawn entirely from the strip. Short as is the time the tooth is down, in such case, there would be some tendency to retard the feed of the strip, but the instant penetration is effected the feed movement of the strip acting upon the rear edge of the tooth and the lower curved edge 24 causes the slotter 18 to swing on its pivot 14, moving in unison with the strip, the spring 20 offering no appreciable resistance. With a short impulse the movement of the slotter in unison with the strip and relatively to the carrier 11 is of very short duration, for upon deenergization of the magnet 1 the carrier rises, and with it the slotter, and the latter is disengaged from the strip and is brought back to normal position by the spring 20. Short as it is, however, the small portion of the edge 24 which has crossed the plane of the strip has acted to cut a short piece or tongue from the strip, the edge 24 acting in conjunction with the sides of the groove 27 to make two parallel shear-cuts in the strip, extending from the point of penetration of the tooth 23 rearward to the point at which the rise of the carrier disengaged the slotter from the strip. Now, if the magnet 1 remains energized for a longer period the angular movement of the slotter relatively to its carrier 11 will be greater, and a greater portion of the curved edge 24 will move across the plane of the strip, the latter

being acted upon by successive parts of said edge, so that a longer tongue will be separated by a shearing cut from the strip, and a long instead of a short perforation will be made, terminated as before by the rise of the carrier when the magnet is deenergized. I have thus provided for the formation of short slots, and for longer ones corresponding to dashes, but a still longer slot will be made if the carrier is held depressed until the entire curved edge 24 has traversed the plane of the strip, but when the point 25 reaches the strip the shearing action ceases automatically, even if the carrier is still depressed, because at that point the edge of the slotter becomes tangent to the plane of the strip. The formation of such maximum slot exerts no more of a retarding action upon the strip than does the formation of the shortest slot, as will be apparent from the foregoing explanation, such long slot being used for an emergency call, or one requiring attention at the main or central station.

The support of the strip by the roll 26 at each side of the groove therein, and the passage of the shearing edge 24 across the plane of the strip and through the groove, as described, effects the clear and sharp shear-cuts which form the parallel sides of each slot, the width of the tongue being equal to the thickness of the slotter 18, the tongues punched out of the strip being indicated at r^x, Fig. 3. By setting the slotter so that the point of its tooth penetrates the strip a slight distance back of the center of the grooved roll, as has been referred to, the slight forward swinging movement imparted to the slotter by the feed of the strip insures the next descent of the tooth far enough behind the slot previously made to leave a proper length of the strip intervening between successive short slots, for as the carrier rises the slotter returns to normal relative position, carrying back the tooth of said slotter so that on its next descent it will penetrate the strip behind the clearance space, the strip moving forward in the meantime.

It will be understood that in a multiple-signal recording apparatus there will be as many slotters as there are signal circuits, and that the supporting roll 26 will have an annular groove 27 for coöperation with each perforator, as shown in Fig. 5. By mounting the roll to rotate freely no drag is exerted upon the strip R passing thereover, and the shearing action upon the strip is facilitated, and I have found in practice that it is advisable to make the diameter of such roll as small as possible.

From the foregoing explanation it will be seen that two factors govern the length of the slot, viz:—the duration of the period during which the slotter-controlling magnet is energized, and the length of the arc of the

curved edge 24 which crosses or traverses the plane of the moving record-receiving strip.

From an inspection of Fig. 5 it will be seen that the employment of a group or set of the slotting devices is readily effected, and with but very slight change in the construction. That is, the several armatures 3^x are shown as bent laterally to bring their free ends nearer together, the carriers 11 being unchanged, and the electro-magnets 1^x are oval in cross-section, rather than circular, with their cores, shown in section, flat instead of cylindrical.

The width of the record-receiving strip will vary according to circumstances, from one-half inch for a single recording device to ten inches for a set of thirty recording devices, a two-inch wide strip being suitable for a four-set mechanism such as shown in Fig. 5, the strip support 26^x having a groove or recess for each slotter.

While I have herein illustrated my invention in detail in connection with a police signal system it is not restricted thereto as it can be used with equal facility for fire alarm systems. In the latter case, inasmuch as all the slots are of uniform length, corresponding to dashes, the segmental shearing edge of the slotter will be made the length required to produce the slot desired, and in actual practice the length of the said edge will be shorter than is required for making the maximum slot in police signal work.

Various changes or modifications in details of construction and arrangement may be made by those skilled in the art without departing from the spirit and scope of my invention as set forth in the claims annexed hereto.

Having fully described my invention, what I claim as new and desire to secure by Letters Patent is:—

1. In recording apparatus in which a record-receiving member is adapted to be moved at uniform speed during the recording of a message, in combination, a slotter having a shearing edge and intermittently movable to intersect the path of movement of said member and effect penetration thereof by the leading end of said edge, and also movable in unison therewith after such penetration, to cause successive portions of said edge to engage and cut a slot in said member, and means to determine the duration of movement of the slotter in unison with the record-receiving member, to thereby regulate the length of the slot.

2. In recording apparatus in which a record-receiving member is adapted to be moved at uniform speed during the recording of a message, in combination, an electrically-controlled carrier vibratable toward and from the path of movement of said member, and a slotter movable with and also relatively to the carrier, and having a shear-

ing edge, to penetrate the said member and to move in unison therewith thereafter, successive portions of the shearing edge crossing and cutting a slot in said member during

5 such movement, the movement of the carrier away from said member terminating the cutting action of the slotter upon the record-receiving member.

3. In recording apparatus in which a record-receiving member is adapted to be moved at uniform speed during the recording of a message, a slotter having an elongated convex shearing edge, means to cause it to penetrate the said member, and means 10 whereby the slotter is moved by and in unison with said member after initial penetration thereof, to cause successive portions of said edge to pass through and cut the record-receiving member and form a slot therein 15 20 while the movement of such record-receiving member is unretarded.

4. In recording apparatus in which a record-receiving member is adapted to be moved at uniform speed during the recording 25 of a message, a slotter movable toward and from said member and also movable in unison therewith, electrically-controlled means to cause the slotter to penetrate said member, and means whereby successive portions of the slotter thereafter engage and shear said member to thereby elongate the initial perforation while the slotter is moving in unison with the record-receiving member.

35 5. In recording apparatus in which a record-receiving member is adapted to be moved at uniform speed during the recording of a message, a grooved support over which said member passes, a slotter having a shearing edge movable into and across the 40 path of movement of said member to penetrate the same and enter the groove, means whereby the slotter is moved in the direction of movement of and by the record-receiving 45 member after initial penetration thereof, to cause successive portions of the shearing edge to engage and make a continuing cut in said member, and electrically-controlled means to govern movement of the slotter 50 toward and from said member and determine thereby the frequency and individual length of the slots formed therein.

6. In recording apparatus in which a record-strip is adapted to be moved at uniform 55 speed during the formation of a record, in combination, a rotatable, annularly grooved roll over which said strip is moved, a slotter movable into and across the path of movement of the strip to penetrate the same and 60 enter the groove in the roll and also movable by and in unison with the strip after penetration thereof, and an elongated, convex, shearing edge on the slotter, successive portions of such edge being brought into engagement with and cutting the strip during

such latter movement of the slotter to complete the slot therein, and means to determine the length of the completed slot in the strip.

7. In recording apparatus in which a record-receiving strip is adapted to be moved longitudinally and continuously during the formation of a record, in combination, a slotter having a tooth and a segmental edge adjacent thereto, an electrically-controlled carrier on which the slotter is pivotally mounted, said carrier being movable toward the strip to cause the tooth of the slotter to penetrate the strip, the segmental edge intersecting the path of movement of the strip and acting, during pivotal movement of the slotter relatively to the carrier, to continue in the form of a slot the perforation made by penetration of the strip by the tooth, retraction of the carrier disengaging the slotter from the strip and terminating the cutting action of the segmental edge, and a device to automatically return the slotter to normal position relative to the carrier after such disengagement.

8. In recording apparatus in which a record-receiving member has a feed movement during the formation of a record, in combination, a slotter adjacent said member and provided with a segmental shearing edge, 95 electrically-controlled means to effect relative movement of said member and slotter to cause the latter to penetrate the former and bring the shearing edge into engagement with said member, and means whereby the slotter is moved by the feed movement of the record-receiving member in unison therewith after penetration, to cause successive portions of the shearing edge to cut said member and complete the perforation 100 105 therein.

9. In recording apparatus in which a record-receiving member is adapted to be moved at uniform speed during the formation of a record, a plurality of independent, intermittently movable slotters each adapted to penetrate said members and to move in unison therewith after such penetration, and a shearing edge on each slotter, successive portions of the edge acting upon said member to 110 cut it and complete a slot of greater or less length, and means to determine the duration of unison movement of each slotter, whereby the length of a slot formed thereby is controlled.

10. In recording apparatus, in combination, a rotatable roll provided with a series of annular grooves and over which a record-receiving strip is adapted to be moved at uniform speed during the formation of a record, a series of slotters independently movable toward and from the strip as it passes over the roll, and also movable in unison with the strip, each slotter having a tooth and a segmental edge adjacent 115 120 125 130

- thereto, to penetrate the strip and enter one of the grooves in the roll, and electrically-controlled means governing the bodily movement of each slotter toward and from the strip, the segmental edge of a slotter whose tooth has penetrated the strip thereafter engaging the strip and continuing the initial perforation while the slotter is moved in unison with the strip.
- 10 11. In recording apparatus, in combination, a recessed support over which a record-receiving strip is longitudinally movable during the formation of a record, and electrically-controlled means including a segmental shear, to intermittently penetrate the moving strip and move in unison therewith, successive portions of the shear engaging the strip after penetration thereof to form elongated perforations or slots therein of
- 15 20 determinate length, the recess in the support permitting penetration of the strip as it moves thereover.
12. In recording apparatus, in which a record-receiving strip is moved at a uniform speed during the formation of a record in combination, an electrically-controlled carrier vibratable toward and from the strip, a slotter pivoted on the carrier and having a pointed tooth and an adjacent segmental
- 25 30 shearing edge, and a strip-supporting roll having an annular groove to receive the tooth after penetration of the strip and to coöperate thereafter with the shearing edge, to cut the strip in the direction of its movement and thereby continue the perforation initiated by the penetration of the tooth.
13. In recording apparatus in which a record-receiving strip is adapted to be moved at uniform speed during the formation of a record, electrically-controlled means including an angularly movable member having a convex shearing edge, to intermittently penetrate the moving strip and form elongated perforations or slots therein
- 35 40 45 of determinate length without retardation of the strip, each penetration of the strip initiating a perforation and angular movement of the member effecting completion thereof by the shearing edge.
- 50 14. In recording apparatus in which a record-receiving strip is adapted to be moved at uniform speed during the formation of a record, electrically-controlled means including a combined penetrating and shearing member movable toward and from and also with the strip, to intermittently penetrate the latter and form elongated, rectangular perforations therein of varying and determinate length but of uniform width, the
- 55 60 movement of said member with the strip effecting the shearing operation without retardation of the strip, each penetration of the strip beginning a perforation.
15. In apparatus for recording tele-

graphic messages, in which a record-receiving strip is adapted to be moved at uniform speed during the formation of a record, in combination, a rotatable, annularly-grooved roll over which the strip passes, a vibratable carrier, a member pivotally mounted thereon and having a penetrating tooth and a segmental shearing edge adjacent thereto, the point of the tooth penetrating the strip and entering the groove in the roll back of the center of the latter, the shearing edge thereafter coöperating to continue the perforation while the said member is moved on its pivot in unison with the strip, a spring to return the pivoted member to normal position relative to the carrier after disengagement with the strip, means to adjust the normal position of the carrier, and message-transmitting means to govern the vibratory movement of the carrier and determine the frequency and length of the perforations to be made in the strip.

16. In recording apparatus in which a record-receiving strip is adapted to be moved at uniform speed during the formation of a record, a vibratable carrier, a member pivotally mounted thereon and movable with and also relative to the carrier, said member having a penetrating tooth and a curved shearing edge, bodily movement of the said member with the carrier toward the strip causing the tooth to penetrate the strip, the shearing edge thereafter crossing the path of movement of the strip and continuing the perforation initiated by such penetration, said pivoted member moving in unison with the strip during the shearing action, electrically-controlled means to govern the vibrations of the carrier and thereby determine the length of each perforation, and means on the pivoted member to terminate, independently of retraction of the carrier, the shearing action after a perforation of maximum length has been made.

17. In a recording apparatus, an annularly-grooved, rotatable roll over which a record-receiving strip is adapted to be longitudinally moved, a slotter having a penetrating portion, a spring-retracted carrier therefor pivotally mounted above the strip and movable toward the same, electro-mechanical means to intermittently depress the carrier and cause the penetrating portion of the slotter to penetrate the strip, longitudinal movement of the strip following penetration thereof effecting movement of the slotter in unison therewith relatively to its carrier, and a convex shearing edge on the slotter, successive portions of such edge acting upon the strip to continue the initial perforation of the strip during such unison movement, the duration of the depression of the carrier determining the length of the perforation.

18. In a recording apparatus, a rotatable roll having an annular groove therein, a slotted having a segmental shearing edge movable into and out of the groove, electrically-controlled means to cause the slotted to intermittently penetrate and move successive portions of its shearing edge across and in cutting engagement with a record-receiving strip adapted to be moved longitudinally over the grooved roll, the duration of each coöperation of the slotted with the strip being determined by said means, and means whereby the shearing edge of the slotted is disengaged from the strip automatically when a slot of maximum length has been made.
19. In recording apparatus in which a strip of paper is moved longitudinally at uniform speed during the formation of a record, in combination, a recessed member adjacent one face of the strip, an opposed, angularly movable, segmentally-edged member adjacent the other face of the strip, and controlling means to effect relative movement of said members and cause the leading end of the segmental edge to penetrate the strip and enter the recess, successive portions of said edge acting upon and shearing the strip during angular movement of the segmentally-edged member, the length of the shear-cut being determined by the amplitude of the arc of said edge which crosses the path of the strip.
20. In recording apparatus, in combination, a member movable toward and from a longitudinally movable record-receiving strip and also movable longitudinally thereof, said member having a shearing edge to pass through and cut the strip, electrically-controlled means to cause the said member to intermittently engage and pass through the moving strip, movement of the latter effecting movement of successive portions of the shearing edge across the strip while the said member is bodily moved in unison with the strip, and acting also to disengage the shearing edge of said member from the strip when a slot of maximum length has been formed, and means to restore automatically the said member to operative condition after disengagement of its shearing edge from the strip.
21. In recording apparatus, in combination, a rotatable, annularly-grooved support across which a record-receiving strip is moved longitudinally during the formation of a record, a shearing member opposite the groove and adapted to penetrate the moving strip, enter and traverse the groove and press the strip against the support, successive portions of said member acting upon and making a shear-cut in the strip at such time, and means to effect and control relative and intermittent movement of the shearing member and support toward and from each other and determine the length of each cut made in the strip.
22. In recording apparatus in which a record-receiving member is adapted to be moved at uniform speed during the recording of a message, in combination, a slotted having an elongated, double edged shearing face and intermittently movable to cause the leading end of the said face to penetrate, and successive portions of each edge thereof to engage and cut a slot in, said record-receiving member while passing therethrough, the slotted simultaneously moving bodily in the direction of travel of and in unison with said member, and means to determine the duration of such coöperation of the slotted and the record-receiving member, to regulate the length of the slot cut therein.
23. A recorder including a marker adapted to cut slots of varying length in the recording tape by means of a continuous shearing action and thereby forming depending tongues of paper.
24. A recorder including a shearing marker adapted to slot the tape to form a tongue, means to operate said marker and means for moving the tape and turning under the tongue as it is moved along.
25. A recorder including a pivoted marker adapted by a continuous shearing action to cut through a marking tape to form open slots therein of variable length.
26. A recorder including a marker adapted to cut slots of varying length in the recording-tape by means of a continuous cutting action, substantially as described.
27. A recorder including a marker adapted to cut slots of varying length in the recording-tape by means of a continuous shearing action and thereby forming tongues, substantially as described.
28. A recorder including a shearing marker adapted to slot the tape to form a tongue by means of a continuous shearing action, and means to operate said marker, substantially as described.
29. A recorder including a shearing marker adapted to cut slots of varying length in the recording-tape by means of a continuous shearing action, substantially as described.
30. A recorder including a slotting-tool adapted to slot the recording-tape, means to operate said tool and hold it in engagement with the recording-tape for different lengths of time, whereby slots of varying lengths are cut in said tape, substantially as described.
31. A recorder including a pivoted-carrier, and segmental slotting-tool pivoted thereto, and means to operate said carrier to force the slotting-tool through the recording-tape and form a slot therein, substantially as described.
32. A recorder including a pivoted-car-

rier, a segmental slotting-tool pivoted there-
to, and means to operate said carrier to force
the slotting-tool through the recording-tape,
and means to operate the recording-tape
while the slotting-tool is in engagement
therewith to move the slotting-tool and form
a slot therein, substantially as described.

33. A recorder including a slotting-tool
adapted to cut slots in the recording-tape

having an initial cutting-tooth, substantially 10
as described.

In testimony whereof, I have signed my
name to this specification in the presence of
two subscribing witnesses.

FRANCIS A. SKELTON.

Witnesses:

JOHN C. EDWARDS,

THOMAS J. DRUMMOND.
